UNITED STATES PATENT OFFICE.

JOSEPH B. DAVIS, OF MONROEVILLE, INDIANA.

SAW-MILL DOG.

SPECIFICATION forming part of Letters Patent No. 334,515, dated January 19, 1886.

Application filed May 18, 1885. Serial No. 165,871. (No model.)

To all whom it may concern:

Be it known that I, JOSEPH B. DAVIS, a citizen of the United States, residing at Monroeville, in the county of Allen and State of Indiana, have invented a new and useful Improvement in Saw-Mill Dogs, of which the following is a specification, reference being had to the accompanying drawings.

My invention relates to an improvement in saw-mill dogs; and it consists in the peculiar construction and combination of devices, that will be more fully set forth hereinafter, and particularly pointed out in the claims.

In the accompanying drawings, Figure 1 is a side elevation of a saw-mill dog embodying my invention. Fig. 2 is a vertical sectional view of the same, taken on the line xx of Fig. 1. Fig. 3 is a detailed sectional view taken on the line yy of Fig. 2.

20 A represents a vertical bar which is to be bolted fast to the standard of the head-block. The upper end of this bar is slotted vertically for a suitable distance, as at a , and from the outer side of this bar, near the lower end thereof, projects a horizontal bracket, a' .

25 B represents a sliding bar, which is slotted at its lower end, as at b , to receive the headed end of the bracket a' , and which has at its upper end a horizontal bracket, b' , that is headed and enters the slot a . By this construction it will be readily understood that the bar B is permitted to slide vertically a suitable distance on the bar A.

30 C represents an eccentric, the shaft c of which is journaled in the bar A, and projects a suitable distance beyond the rear side of the said bar. To this projecting end of the eccentric shaft is secured a lever, D.

35 E represents a rod which is pivoted at its upper end to the sliding bar B. The lower end of this rod is formed into an eccentric-strap, e , which encircles the eccentric C. A box, F, slides upon the bar B, and in the upper end of this box is journaled an eccentric cam, G. To this cam is secured a lever, H. When the lever H is raised in the position shown in solid lines in Fig. 1, the cam is turned so as to be out of contact with the face of the bar B, and the box F is then free to be 40 raised or lowered on said bar. When the lever H is lowered in the position shown in dotted lines in Fig. 1, the cam bears against

the face of the bar B, and the box F is im- movably secured to said bar. A horizontal opening is made in the lower end of the box 55 F, and through this opening passes the ex- tended arm i of the bit I. To the under side of this arm is secured a flat spring, K, which is provided with teeth k , that engage with an abutment or shoulder, f , that is formed in the 60 box F. This toothed spring prevents the bit from being drawn forward except by aid of the operator; but when the bit is extended and a log rolls against it the teeth will dis- engage themselves and allow the bit to get in po- 65 sition.

The operation of my invention will be readily understood from the foregoing description and by reference to the accompanying drawings.

A saw-mill dog thus constructed is cheap 70 and simple, is easily operated, and is thor-oughly efficient in use.

I am aware that it has been heretofore pro- posed to use a laterally-sliding dog having a series of notches, and a bearing-spring in com- 75 bination with a mortised head having a tooth for engaging with the notches in the dog, and this construction I disclaim. My invention differs from this in that I provide the dog with a toothed spring instead of having the teeth 80 in the dog, and by so doing I gain an impor- tant advantage.

In the construction disclaimed, in order to adjust the dog when engaged with a log it would be necessary to press the inner end of 85 the dog up against the pressure of the spring to release its notch from the toothed head, and thus necessarily embed the point of the dog more firmly in the log, requiring great exertion, while by simply raising the free end 90 of my spring its teeth are disengaged and the dog released, as will be very readily under- stood.

Having thus described my invention, I claim—

1. The combination, in a saw-mill dog, of the rigid bar A, having the headed bracket a' and the slot a , the sliding bar B, having the slot b , in which the bracket a' works, and the headed bracket b' , working in slot a , means 100 for raising and lowering the sliding bar, the box F on said bar, having the slotted opening, the shoulder f , and the cam for clamping the box to the bar, with the dog I, the bearing-

spring K, fast thereto and having the teeth *k* for engaging with the shoulder *f*, for the purpose set forth, substantially as described.

2. The combination of the sliding bar B, the box F on said bar, having the slotted opening, the shoulder *f*, and the cam for clamping the box to the bar, with the dog I, the bearing-spring K, fast thereto, and having the teeth *k*, for engaging the shoulder *f*, substantially as described.

In testimony that I claim the foregoing as my own I have hereto affixed my signature in presence of two witnesses.

JOSEPH B. DAVIS.
